BOAT

B. J. Robbins, P.O. Box 567, Marshall, Tex. 75670;
 Sanford L. Patterson, 3225 Autumn Lane, Shreveport,
 La. 71109; and Raymond W. Spencer, 600 Lynoak,
 Marshall, Tex. 75670

Filed Mar. 18, 1971, Ser. No. 125,913

Term of patent 14 years

Int. Cl. D12—06

U.S. Cl. D71—1 Q

FIG. 1 is a top plan view of the boat showing our new design.

FIG. 2 is a side elevational view thereof.

FIG. 3 is a rear elevational view of the boat.

FIG. 4 is a cross sectional view thereof, taken substantially along a plane as indicated by the line 4—4 of FIG. 1.

We claim:

The ornamental design for a boat, as shown.
